UNITED STATES PATENT OFFICE

2,499,945

BURETTE HOLDER

Guy H. Burrell, Pittsburgh, Pa., assignor to Burrell Technical Supply Company, Pittsburgh, Pa., a corporation of Pennsylvania

Application July 3, 1946, Serial No. 681,333

2 Claims. (Cl. 248—124)

1

This invention relates to new and useful improvements in burette holders for laboratory use, and it is among the objects thereof to provide an adjustable burette holder embodying clamping means for the burette which is designed to yieldingly hold the burette against a plurality of spaced stationary abutments and to be displaceable for quick adjustment by a thumb latch.

The invention will become more apparent from a consideration of the accompanying drawing, constituting a part hereof, in which like reference characters designate like parts, and in which

Fig. 1 is a front elevational view of a burette holder embodying the principles of this invention;

Fig. 2 is a side elevational view thereof; and

Fig. 3 a top plan view.

In the drawing the numeral 1 designates a base having a cylindrical tube 2 constituting a standard on which a clamping bracket 3 is mounted for sliding adjustment thereon. The bracket 3 is provided with a hollow lug 4 that envelops the tubular standard 2, as shown in Fig. 3, one portion of the lug being V-shaped, as shown at 5, and the strap portion having a threaded boss 6 for receiving the clamping screw 7. The clamping bracket is provided with studs 8 covered with rubber 9 and shaped to form a V-seat 10 for the burettes 11, the burette engaging the top and bottom lugs 8 as shown in Fig. 2.

The burettes are held in abutting engagement with the lugs 8 by a clamping lock 12 which is a rubber covered stud member 13 mounted on a bell crank lever 14 pivoted on the clamping bracket 3 by screws 15. As shown in Fig. 1, the levers are provided with an arm 16 having a thumb lug 17, and the bracket 3 is shaped to form another arm 18 in alignment with the arm 16 of the clamp. The clamp arm 14 is normally urged in clamping engagement with the burette 11 by a coil spring 19 with the thumb lug 17 spaced away from the arm 18 as shown in Fig. 1. To adjust the burette and the clamp it is only necessary to engage the lug 17 and arm 18 between the thumb and forefinger and bring them together, as shown in dotted lines. This compresses spring 19 and moves the lever arm 14 away from the burette, through an arc in an upward direction, as shown by the dotted lines in Fig. 1. The burette may then be adjusted with the other hand, and when the thumb lug 17 is released the lug 12 effects intimate engagement of the burette 11 with the stationary members 8 to hold it in frictional engagement therewith.

As shown in the drawing, two of such burette clamping elements are provided on one mounting bracket and a symmetrical structure is available through the use of the single coil spring with the individual clamping lugs 17 for each of the clamp levers 14. The design lends itself to an

2

inexpensive construction and to a convenient use in laboratory work.

Although one embodiment of the invention has been herein illustrated and described, it will be evident to those skilled in the art that various modifications may be made in the details of construction without departing from the principles herein set forth.

I claim:

- 10 1. In a burette holder, a clamping bracket mounted for sliding movement on a column, said bracket being of substantially yoke shape with a plurality of downwardly depending fingers and having arms for supporting abutments that are vertically spaced for engaging one side of a burette, a plurality of levers mounted on said bracket having arms extending beyond the vertically spaced abutments and each carrying a gripping member for engaging the opposite side of the burette, said levers having downwardly depending arms and thumb lugs in alignment with the downwardly depending arms of the bracket, and spring means connecting said levers to each other whereby to normally bias each of said levers into abutting engagement with the burette, and normally maintain the depending lever arms and bracket arms in spaced relation for gripping engagement to displace either of the levers for releasing the burette.
- 20 2. In a burette holder, a base, a column extending on said base, a clamping bracket mounted on the column having clamping means for securing the bracket in adjusted position on said column, said bracket having a plurality of horizontally extending arms at the top thereof and a plurality of depending arms therebeneath, gripping members mounted on said arms in vertically spaced alignment, levers pivotally mounted on said bracket having arms extending substantially horizontally carrying a gripping abutment for engagement of a burette, spring means interconnecting the levers to normally bias them to gripping engagement with the burette to hold the latter against the vertically spaced gripping abutments, said levers having downwardly depending arms with thumb lugs and said bracket having downwardly depending arms in alignment with said lever arms to constitute with said thumb lugs gripping means for separately releasing said levers out of engagement with the burette.
- 30 35 40 45 50
